APPARATUS FOR PRODUCING ARCH SUPPORTS

Michael L. Niles, Milwaukee, Wis., assignor to
 Van Horne Kaestner Leather Co., Milwaukee,
 Wis., a corporation of Wisconsin

Application September 17, 1949, Serial No. 116,334

3 Claims. (Cl. 12—1)

1

The present invention relates generally to improvements in the art of manufacturing shoes, and relates more particularly to an improved method of and apparatus for forming arch supports or so-called molded cookies for shoes.

A primary object of my invention is to provide an improved method of and unitary device for rapidly producing effective molded arch supports in an extremely simple, efficient, accurate and economical manner.

It has heretofore been customary, in the manufacture of shoes, to provide supporting means for the longitudinal arch of the wearer's foot. In some cases, these arch supports are formed of an integral part of the insole blank in the form of a side wing extension which is shaped by hand in a suitable manner to conform with the shoe last; and in other cases a separate flat plate-like element or cookie, is attached to the side portion of the insole and is thereafter manually shaped to the last as the shoe is built. These types of arch supports are manually formed of leather or the like which is relatively flexible; and because of the nature of the material and the manner of hand molding the support as the shoe is built, considerable difficulty has been encountered with such supports in that they do not retain their shape but rather break down prematurely under wear and thereby become ineffective for the intended purpose.

It is therefore a more specific object of this invention to provide a novel mode of efficiently producing improved preshaped arch supports of relatively flexible materials which obviate the difficulties heretofore present.

Another specific object of the invention is to provide an improved apparatus for effectively preshaping arch supports which is extremely simple, compact and durable in construction and highly efficient, rapid and labor-saving in actual operation.

Another specific object of this invention is to provide an improved molding machine for quantity production of preshaped arch supporting members which may be readily operated by a novice and wherein all parts may be quickly assembled and/or dismantled with the aid of ordinary tools for inspection, replacement or repair.

An additional specific object of my present invention is to provide an improved machine for permanently shaping arch supports prior to the attachment thereof to the shoe insole, and wherein the parts may be readily interchanged to produce either left or right foot supporting members.

Still another specific object of the present invention is to provide an improved method of efficiently preshaping arch supports formed of leather or the like and especially adapted for use with Goodyear welts for prolonging the life of the shoe and the effectiveness of the support.

A further specific object of the present invention is to provide an improved method of forming an arch supporting cookie from a flat blank which comprises, shaping the blank to finally form the supporting body by clamping the same with a longitudinal edge projecting therefrom, and thereafter finally distorting the projecting edge while retaining the blank firmly clamped to form a flange extending in one direction throughout the major length of the body and a lip projecting in an opposite direction with respect to the body.

A still further specific object of the present invention is to provide an improved apparatus for forming an arch supporting cookie comprising, relatively movable clamping members having adjacent cooperating surfaces for receiving and clamping the major portion of a flat blank therebetween to distort and finally shape the supporting body, the clamping members terminating short of a longitudinal edge of the blank to cause the edge to project beyond the members, and a flange-forming member movable relative to the clamping members to distort the projecting edge portion of the blank to form an attachment flange.

These and other specific objects and advantages of the improvements will be apparent from the following detailed description.

A clear conception of the several features constituting my present invention, and of the steps involved in my improved method, and of the mode of constructing and of utilizing improved arch support forming apparatus embodying the improvements, may be had by referring to the drawings accompanying and forming a part of this specification, wherein like reference characters designate the same or similar parts in the various views.

Fig. 1 is a fragmentary perspective view of a typical arch-supporting cookie forming apparatus constructed in accordance with my invention, and showing the several parts thereof in inactive starting positions;

Fig. 2 is a similar fragmentary perspective view of the machine, showing the clamping and forming members in operative closed position with a leather blank clamped therebetween and with

the flange-forming member or wiper plate at the start of its downward stroke;

Fig. 3 is a like fragmentary perspective view of the apparatus, showing the clamping members still in clamping position but with the wiper plate moved downwardly and in the act of performing its flange forming operation on the protruding edge of the blank;

Fig. 4 is another fragmentary perspective view of the device with the wiper plate raised after completion of its operation and with the clamping jaws again spread apart to reveal the finally formed cookie;

Fig. 5 is a perspective view of a typical inner sole for a right shoe, showing one of the improved molded cookies secured to the bottom face thereof;

Fig. 6 is a perspective view of a lower clamping member for forming cookies for left shoes, as distinguished from that for right shoes shown in the preceding views, and with a finally formed cookie therein;

Fig. 7 is a perspective view of a flange-forming wiper plate used with the clamping member of Fig. 6; and

Fig. 8 is a fragmentary schematic side view of the several cooperating parts.

While the method and apparatus constituting the present invention has been shown and described herein as being especially applicable in connection with the production of arch supporting cookies of a particular design illustrated as being secured to the bottom face of a known type of shoe insole in a particular manner, it is not my desire or intent to thereby unnecessarily limit or restrict the scope or utility thereof; and it is also contemplated that specific descriptive terms employed herein be given the broadest possible interpretation consistent with the disclosure.

In accordance with my present improved method of forming arch supporting cookies, I initially cut a relatively thin and flat blank of leather to the desired size and configuration, the edges of which are then skived in the usual manner. I then shape the blank to finally form the arch supporting body of the cookie by clamping the same under pressure with a longitudinal edge projecting therefrom. Thereafter, while retaining the supporting body of the blank firmly clamped, I finally distort the projecting edge of the blank in one direction throughout its major length and in an opposite direction throughout its remaining length, thereby forming an attachment flange extending in said one direction throughout the major length of the finally shaped cookie and a lip projecting in an opposite direction than the flange with respect to the cookie body. The final arch supporting cookie thus produced is accordingly molded to a definite predetermined shape with a convenient attachment flange and lip cooperable with the bottom rib of the usual insole, thereby imparting effectiveness to the cookie as an arch support and also increasing its effectiveness and length of time it serves in aiding to maintain the shape of the shoe.

In carrying on commercial exploitation of my improved arch supporting cookie forming method, the apparatus shown in the accompanying drawings has proven especially efficient in rapidly and economically producing the cookies in large quantities. Referring to the drawings the improved cookie forming apparatus shown therein comprises, in general a main frame 10 having

a lower stationary work supporting bed or base 11 and an upper bridge piece 12 secured to the bed 11 by vertical tie rods 13; a lower clamping member or forming die 14 fixedly mounted on the bed 11 and having an upper work molding surface 15; an upper clamping member or forming die 16 supported by the bridge piece 12 for vertical movement relative to the lower die 14 and having a lower work engaging and clamping surface 17 cooperable with the surface 15 of the die 14; a pair of elongated vertical guide members 18 rigidly secured to the bridge piece 12 of the frame 10 by bolts 19 or the like and adapted to receive and guide a carrier member or slide 20 therebetween, the slide 20 being vertically movable along the guides 18 by means of power applied to the upper end of a drive rod 21 in any well known manner; and a flange forming member or wiper plate 22 secured to the slide 20 as by means of screws 23 or the like and movable therewith past the clamping members 14, 16 as will hereinafter more fully appear.

The forming dies 14, 16 are provided with plain front faces 24, 25, respectively, lying in the same vertical plane; and the lower die 14 has an extension 26 at one end of its face 24, the upper end of which projects upwardly and outwardly away from the molding surface 15 thereof to form an inclined lip 27, while the upper die 16 has an extension 28 at the end of its face 25, the lower end of which is correspondingly inclined as at 29 for cooperation with the lip 27. As shown, the lower die 14 may be conveniently mounted on the supporting bed 11 by means of a mounting plate 30 secured to a medial portion of the bed 11 by bolts 31 or the like, the plate 30 carrying a supporting block 32 to which the base 33 of the die 14 is rigidly attached in any suitable manner. The upper die member 16 is vertically actuated by hydraulic pressure or the like applied in a well known manner to an actuating rod 34 such as shown in Fig. 8 the actuating mechanism, not shown, being supported by the bridge piece 12 of the main frame 10 in a convenient manner. As indicated hereinabove, the wiper plate 22 is secured to the slide 20 for vertical movement therewith; and referring particularly to Fig. 7, this plate 22 has a wiping surface 35 conforming to and cooperable with the front faces 24, 25 of the respective dies 14, 16 and a cutting edge 36 cooperable with a side of the extension 26, 28 upon downward movement of the plate 22. The drive rod 21 may be secured to the slide 20 in any suitable manner, as by means of a pivot pin 37 piercing lugs 38 formed integral with the slide 20; and this rod 21 is also vertically actuated in a known manner by hydraulic pressure or the like, the length of the stroke being suitably adjustable so as to vary the distance of travel of the slide 20.

The operation of the device thus described in the production of arch supporting cookies is as follows. With the upper die 16 and wiper plate 22 raised as shown in Fig. 1, to inactive position, an initially prepared flat blank 39 of leather or composition material is positioned between the adjacent forming surfaces 15, 17 of the respective dies 14, 16 with a longitudinal edge of the flat blank 39 projecting outwardly from the front faces 24, 25 of the dies a distance approximately equal to the width of the lip 27 formed by the extension 26. The upper die 16 is then actuated downwardly under pressure to firmly clamp the blank 39 between the cooperating forming surfaces 15, 17 of the dies as shown in Fig. 2, there-

by shaping the blank to finally form the arch supporting body of the cookie with the major length of the longitudinal edge of the blank 39 projecting outwardly from the die faces 24, 25 and the remaining length of the longitudinal edge clamped between the adjacent inclined surfaces 27, 29 of the extensions 26, 28 respectively. The slide 20 is thereafter actuated downwardly, as illustrated in Fig. 3, with the surface 35 of the plate 22 wiping over the faces 24, 25 of the dies, the cutting edge 36 of the plate 22 cooperating with the side of the extension 26 of the lower die 14 to cut the projecting edge of the blank 39 into a major and a minor length with the minor length of the blank edge remaining firmly clamped between the upwardly inclined extension surfaces 27, 29 as the major length thereof is distorted downwardly by the downward movement of the wiper plate 22. After passing the projecting edge of the blank 39, the wiper plate 22 is withdrawn upwardly and the upper die 16 is likewise raised with the finally molded cookie being shown in Fig. 4 as resting upon the lower die 14.

The arch supporting cookie thus formed comprises a main arch supporting body or side portion 40 having an integral attachment flange 41 projecting therefrom in one direction throughout the major length of one longitudinal edge and an attachment lip 42 projecting therefrom in another direction throughout the remaining length of the longitudinal edge; and the molded cookie is adapted for attachment to the bottom ribbed face of the usual shoe insole 43 as illustrated in Fig. 5. While the apparatus has been specifically shown in Figs. 1 to 4 inclusive with lower and upper forming dies 14, 16 respectively and a wiper plate 22 adapted for producing arch supporting cookies for right shoes, it should be understood that arch supporting cookies for left shoes may be readily produced in like manner with the same apparatus by merely changing the dies and wiper plate in an obvious manner; and Figs. 6 and 7 respectively show a lower forming member or die 14 for left shoe cookies and a wiper plate 22 therefor, a finally molded cookie being shown in position in the die 14 of Fig. 6.

From the foregoing detailed description, it is believed apparent that my present invention provides an improved molded arch supporting cookie adapted to be manufactured from relatively inexpensive stock and molded to a definite predetermined shape formed for convenient attachment to the usual insole to effectively shape the shoe while affording an extremely efficient arch support. By utilizing the improved method in the manufacture of these cookies, the production rate thereof may be enhanced to a maximum with the utmost economy, efficiency and accurateness. Obviously, the improved apparatus shown and described herein for producing the cookies in accordance with my present method is simple and compact in construction and efficient in operation. The device comprises relatively few parts, all of which are readily accessible for inspection, adjustment, replacement, and/or repair; and the dies 14, 16 and wiper plate 22 may all be quickly removed and replaced by corresponding dies and wiper plate for either left or right shoe cookies, as desired, by merely upwardly removing the carrier 20, after removal of the pin 37 and thereafter removing screws 23 to detach the plate 22 and by also unbolting the dies 14, 16 from their respective supports. The

device may be operated by a novice with provision of suitable controls for the pressure mechanisms, and all hand molding operations are eliminated through use of the machine. The improved apparatus has, in fact, gone into extensive commercial use and has proven highly successful and practical in actual operation.

It should be understood that it is not desired or intended to limit this invention to the exact steps of the production method or to the precise details of construction of the apparatus, herein shown and described, since various modifications within the scope of the appended claims may occur to persons skilled in the art to which this invention pertains.

I claim:

1. Apparatus for forming an arch supporting cookie from a flat blank comprising, a lower clamping member having an upper work molding surface, an upper clamping member movable vertically relative to said lower clamping member and having a lower work engaging surface cooperable with the upper surface of said lower member to clamp the blank therebetween, said lower and upper members having corresponding front faces lying in the same vertical plane terminating short of a longitudinal edge of the blank to cause said edge to project beyond the front faces of said members, an extension projecting outwardly beyond said front faces at one end of each of said members, said extensions having adjacent cooperating surfaces for gripping a lip portion of said projecting edge of the blank, and a wiper plate vertically movable relative to said members and along the front faces thereof, said plate having a wiping surface cooperable with the faces of said members and a cutting edge cooperable with said extensions to distort and cut the free projecting edge portion of the blank to form an attachment flange laterally beyond said lip portion along said longitudinal edge.

2. Apparatus for forming an arch supporting cookie from a flat blank comprising, a lower clamping member having an upper work molding surface, an upper clamping member movable vertically relative to said lower clamping member and having a lower work engaging surface cooperable with the upper surface of said lower member to clamp the blank therebetween, said lower and upper members having corresponding front faces lying in the same vertical plane terminating short of a longitudinal edge of the blank to cause said edge to project beyond the front faces of said members, an extension projecting outwardly beyond said front faces at one end of each of said members, said extensions having adjacent cooperating upwardly directed surfaces for gripping a lip portion of said projecting edge of the blank and distorting the same in one direction, and a wiper plate vertically movable relative to said members and along the front faces thereof, said plate having a wiping surface cooperable with the faces of said members and a transverse cutting edge cooperable with said extensions to simultaneously distort and cut said projecting edge portion of the blank to form a lip and an oppositely directed attachment flange along said longitudinal edge thereof.

3. Apparatus for forming an arch supporting cookie from a flat blank comprising, a lower clamping member having an upper work molding surface, an upper clamping member movable vertically relative to said lower clamping member and having a lower work engaging surface co-

operable with the upper surface of said lower member to clamp the blank therebetween, said lower and upper members having corresponding front faces lying in the same vertical plane terminating short of a longitudinal edge of the blank to cause said edge to project beyond the front faces of said members, means associated with the front faces of said members for gripping and distorting a lip portion of said projecting edge of the blank in one direction, and a wiper plate vertically movable relative to said members and along the front faces thereof to distort said projecting edge portion of the blank adjacent the projecting lip portion thereof to form an attachment flange along the major length of said longitudinal edge, 10

8
said plate having a cutting edge cooperable with said lip gripping means to cut said flange adjacent said lip portion.
